UNITED STATES PATENT OFFICE

123,818

DESIGN FOR A RANGE OR SIMILAR ARTICLE

Elmer D. Pellegrin, Woodstock, Ill., assignor to
Geo. D. Roper Corporation, Rockford, Ill., a
corporation of Illinois

Application March 16, 1940, Serial No. 90,981

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Range or Similiar Article, of which the following is a specification, reference being had to the accompanying drawing, forming part thereof.

In the drawing:

Figure 1 is a perspective view of a range or similar article showing my new design with the light and mirror casing in lowered position;

Fig. 2 is a fragmentary perspective view along similar lines with the light and mirror casing in raised position;

Fig. 3 is an end elevational view on an enlarged scale of the light and mirror fixture;

Fig. 4 is a front elevational view thereof, and

Fig. 5 is a top plan view thereof.

The dominant features of the design are those shown in full lines.

I claim:

The ornamental design for a range or similar article, substantially as shown and described.

ELMER D. PELLEGRIN.
